Primary Examiner — Susan Bennett Hattan*Assistant Examiner* — Suzanne E Tisdell(74) *Attorney, Agent, or Firm* — Reising Ethington, P.C.(57) **CLAIM**

The ornamental design for a vehicle grille lower, as shown and described.

DESCRIPTION

FIG. 1 is a perspective view of the vehicle grille lower;

FIG. 2 is a front view thereof;

FIG. 3 is a side view thereof; and,

FIG. 4 is a top view thereof.

The broken lines in the drawings illustrate portions of the vehicle grille lower that form no part of the claimed design.
